UNITED STATES PATENT OFFICE.

FRANCIS H. RICHARDS, OF HARTFORD, CONNECTICUT.

MECHANICAL MOVEMENT.

No. 841,444.

Specification of Letters Patent.

Patented Jan. 15, 1907.

Application filed May 15, 1901. Serial No. 60,307.

To all whom it may concern:

Be it known that I, FRANCIS H. RICHARDS, a citizen of the United States, residing at Hartford, in the county of Hartford and State of Connecticut, have invented certain new and useful Improvements in Mechanical Movements, of which the following is a specification.

This invention relates to mechanical movements; and it has for its object the provision of an organization of devices or elements whereby a regular and uniform movement may be converted into one of an opposite character and the continuous forward movement of a driver be transformed into a periodically varying movement of a driven member.

In the drawings accompanying the present specification, Figure 1 is an end elevation of an organization of devices embodying the present mechanical movement. Fig. 2 is a sectional side elevation of the parts shown in Fig. 1, and Fig. 3 is a diagrammatic view illustrating the kinematic features of the present mechanical movement.

Similar characters of reference designate like parts in all the figures of the drawings.

The driving member is herein shown as a pinion, the motion of which is transmitted through an intermediate device, serving to alter the continuous rotary motion of the pinion constituting the driving member and to cause the driven member, shown herein in the form of a rotary shaft, to partake of a movement of rotation varying periodically.

In the illustrated embodiment of the present invention motion is imparted to the member constituting the member herein referred to as the "driving" member from a power-shaft S, which is shown journaled in appropriate

bearings 10, supported on pedestals or uprights b b', erected from a bed-plate B of any suitable construction and which may be, in fact, a portion of the machine or mechanism framing to which the present mechanical movement is applied. To this shaft S a driving-pulley s may be secured, by means of which the shaft may be rotated from some source of power. There is also affixed to this shaft a gear-wheel 21, which serves to drive, through an engaging gear-wheel 22, a pinion 23, constituting the driving member and whose axis, as illustrated, is coincident with the axis of the gear-wheel 22. In the particular construction shown, the pinion, provided with an elongated hub 27, and the gear-wheel

22 are both secured to a shaft 11, mounted in a bearing 12, supported on the pedestal b'.

Motion is imparted to the shaft 2, constituting the member herein referred to as the "driven" member, to effect an irregular or intermittent rotary motion thereof by means of an intermediate differential train comprising a gear-wheel 24, meshing with said pinion 23 and with an internal gear-wheel 25, attached to the shaft 2. This intermediate gear-wheel 24 is adapted to be swung in a circular arc whose center lies in the axis of the pinion 23, and to enable this to be effected the intermediate gear-wheel may be rotatably mounted on an arm or rocker 26, whose lateral tubular extension 26^b is journaled to the exterior of the elongated hub of the pinion 23, about which hub the arm may be oscillated to carry the gear-wheel 24 to and fro in the annular space between the pinion and the internal gear-wheel.

For the purpose of securely supporting the several parts there is shown as a feature of constructive detail an extension c on the supporting-shaft 11, having a bearing in an axial recess formed in the end of the shaft 2.

The arm 26 is oscillated as aforesaid by means of a crank motion, such as a crank and crank-pin, provided on the main shaft S, and which taken together are designated generally by 28. A connecting-rod 29 places this crank 28 in operative connection with a projecting arm 30 of the tubular extension 26^b of the rocker 26, and although I have specified a crank and crank-pin as an instance of a crank motion by which the rocker 26 may be operated it is obvious that an eccentric would effect substantially the same results, it being but another instance of the mechanical movement known as a "crank motion," since it operates upon the same principle as a crank. In using the term "crank motion" therefore I wish to include this and like equivalents.

The action of this transmitting device will be readily understood upon reference to the diagrammatic view of Fig. 3 with the aid of the following explanation. It should be stated at the outset that as the gear-wheels 21 and 22 are shown their diameters are equal. Hence the pinion 23 will revolve at the same speed as the main shaft S. Referring now to the diagrammatic view, s' represents the intersection of the axis of the shaft S with the plane of the paper on which the view is depicted and 25' the corresponding intersec-

tion of the axis of the internal gear-wheel 25, which axis, it is apparent, coincides with the axis of the pinion 23 and also of that of the driven member or shaft 2. The pitch-circle 5 of the gear-wheel 21 on the main shaft S is represented by the dotted circle 21^a, 21^b, and 21^c and the pitch-circle of the engaged gear-wheel 22 by the dotted circle 22^a, 22^b, and 22^c. The pitch-circle of the internal gear-wheel 25 is represented by the dotted circle 25^a, 25^b, and 25^c and the pitch-circle of the pinion 23 by the dotted circle 23^a, 23^b, and 23^c. Six arbitrary positions of the crank 28 on the main or power shaft are chosen for the purpose of illustrating the action of the device, and they are conveniently taken so as to show collectively the progressive movement of the crank through three hundred and sixty degrees of an arc. These positions 15 are indicated by x' , x^2 , x^3 , x^4 , x^5 , and x^6 , and the corresponding positions of the pivotal axis of the connection between the connecting-rod 29 and the arm 30 (this arm being indicated in dotted outline for its corresponding positions) are indicated by y' , y^2 , y^3 , y^4 , y^5 , and y^6 , respectively.

Assuming the power-shaft S to be rotating in the direction of the arrow at the lower left-hand portion of the diagram, it is plain 30 that the direction of rotation of the pinion 23 will be in the direction of the arrow adjacent to the circle 23^a, 23^b, and 23^c representing its pitch-line. Hence the direction of the rotation imparted to the intermediate gear-wheel 24 will be that of the arrow or left-handed, contrary to the direction of motion 35 of the hands of a watch with its axis, let it be assumed, in the position indicated by z' , which corresponds to the mentioned positions 40 x' and y' . The pitch-circle of this intermediate gear-wheel 24 is also represented in dotted outline, the figure indicating the positions assumed by it for the given positions of the crank 28. If now there were no translational movement of the axis of this intermediate gear-wheel 24, the internal gear-wheel 25 would be rotated continuously in the same direction as the former gear, but since, as already explained, the intermediate 45 is adapted to be oscillated by the crank 28, a movement of the latter through a distance represented by the arc x' x^2 will move the pivotal axis of the connecting-rod joint from y' to y^2 and carry the center of the intermediate gear-wheel from z' to z^2 —that is, in the 50 direction that the described rotation of the intermediate gear-wheel 24 tends to turn the internal gear-wheel 25. This movement of the crank from x' to x^2 corresponds to one- 55 sixth of the full rotation of the main or power shaft, and since, as already explained, the pinion or driving member 23 rotates at the same speed as this shaft and the internal gear-wheel 25 in this case is twice the diameter 60 of the pinion the internal gear-wheel will

be rotated one-twelfth of a turn, leaving out of account the swinging of the intermediate gear-wheel. Taking this translational movement of the axis of the intermediate into account, the one-twelfth rotation of the internal 70 gear-wheel 25 will be increased by an amount of angular movement, as the intermediate gear-wheel rolls over the pinion, corresponding to the movement of its center from z' to z^2 . For the further one-sixth of a rotation 75 of the main shaft S through the arc x^2 x^3 , the said pivotal axis of the connecting-rod joint will move from y^2 to y^3 , and the internal gear-wheel will be rotated an additional one-twelfth of a turn plus the added fraction of 80 a complete rotation, due to the swinging of the intermediate gear-wheel center from point z^2 to z^3 . Therefore for two-sixths of a full rotation of the main shaft the internal gear-wheel 25 will be rotated two-twelfths of 85 a rotation plus that fraction of a complete rotation, due to the rolling of the intermediate gear-wheel over the pinion as its center moves through the arc z' z^3 .

When the first portion of the next one-sixth rotation of the crank 28 has occurred, it will take the position x^4 and the pivotal axis of the connecting-rod joint the position y^4 , the pivotal axis shifting back again to the position y^4 upon the completion of the one-sixth of the rotary movement with the crank at the point indicated by x^4 . The position of the intermediate gear-wheel center corresponding to this position y^4 is z^4 , there being consequently a further net rotative movement given to the internal gear-wheel 25 of one-twelfth of a full turn, together with the fraction of a turn, due to the rolling of the intermediate gear-wheel as its center moves through the arc z^3 z^4 . The shaft S has now 100 rotated one-half of a full turn, while the internal gear-wheel 25 has made three-twelfths, or one-quarter of a rotation plus that fraction of a rotation due to the rolling of the intermediate gear-wheel as its center moves 105 through the arc z' z^4 . Now the angular movement imparted to the internal gear-wheel 25 by reason of the swinging and consequent rolling of the intermediate 110 24 as its center moves from z' to z^4 is represented by 115 the sum of the angle subtended by the arc z' z^4 and the angle subtended by the arc of the pitch-circle of the pinion 23, over which the pitch-circle of the intermediate gear-wheel 24 rolls as its center moves from z' to z^4 120 after this arc has been laid off on the pitch-circle of the internal gear-wheel. The length of the arm 30 and the relation of the crank and arm to each other and to the other parts may be made such that these two angles are together approximately equal to one-quarter of a turn of the internal gear-wheel. Hence for the particular semirotation of the crank 28 considered the driven member or 125 shaft 2 will be rotated one-half a turn. 130

For the next one-sixth rotation of the crank—that is, from x^4 to x^5 —the corresponding movement of the pivotal axis of the connecting-rod joint will be from y^4 to y^5 , carrying the intermediate gear-wheel center from z^4 to z^5 —that is, in a direction the reverse of that in which the rotation of the intermediate 24 tends to turn the internal gear-wheel 25. The conditions are now reversed, the rotative motion due to the swinging of the intermediate, which before was added to that due to the effect of the rotating pinion 23, now acting to diminish this latter effect. The relations and dimensions to the various 15 engaging gear-wheels and other parts concerned may be as pointed out above and are here such as to cause the tendency to reverse the rotation arising from the rolling of the intermediate gear-wheel backward over the pinion 23 as its center moves through the arc $z^4 z^5$ to be approximately equal to one-twelfth of a full turn of the internal gear-wheel. Hence as the rotative movement of the intermediate gear-wheel, due solely to 25 the rotation of the pinion 23, is in amount sufficient to turn the internal gear-wheel forward one-twelfth of a complete turn the intermediate will simply roll backward along the teeth of the internal gear-wheel and cause 30 substantially no motion of the latter. For a similar reason, substantially no movement of the internal gear-wheel occurs for the next similar fraction of a complete rotation of the crank—that is, from x^5 to x^6 —which results in 35 a movement of the pivotal axis of the connecting-rod joint from y^5 to y^6 and the transfer of the intermediate gear-wheel center from z^5 to z^6 .

During the first portion of the last one-sixth of the full turn of the crank—that is, from x^6 to x' —the pivotal axis of the connecting-rod joint will move to the position y' , returning to the position y^6 , however, at the completion of the rotation of the crank. 40 The final position of the center of the intermediate 24 will be at z' , it having moved backward—that is, in the opposite direction to that in which the internal gear-wheel 25 is naturally rotated by the pinion—a distance 45 indicated by the arc $z^6 z'$, causing as a result the internal gear-wheel to rotate forward a full one-twelfth of a rotation minus that fraction of a rotation due to the rolling backward of the intermediate as its center moves 50 through the arc $z^6 z'$. This completes the second semirotation of the crank 28, and it will be evident from what has been said in a preceding paragraph relative to the effect produced by the rolling of the intermediate 55 gear-wheel over the pinion 23 that since its effect is reversed in the second semirotation the internal gear-wheel makes but one-half a turn for each full rotation of the crank. In other words, during the translational movement of the intermediate gear-wheel center 60

from z' to z^4 the internal gear-wheel 25, and consequently the driven member, rotates forward. The speed of this forward movement of the driven member begins to slacken, however, as the intermediate gear-wheel center nears the position z^4 and is rapidly reduced to zero as the intermediate gear-wheel swings in the opposite direction—that is, from z^4 toward z' —until as the intermediate gear-wheel center approaches the latter position the rotative movement of the internal gear-wheel is again initiated and increases in rapidity, which it continues so to do as it passes this point, and the translational motion of the center again takes place in a forward direction. The complete oscillation of the intermediate gear-wheel 24 therefore causes the internal gear-wheel, and hence the driven member, to lose such a fraction of a rotation when the intermediate swings in one direction as it gains when it swings in the opposite direction. 75

It is evident from the foregoing description and explanation that the present mechanical movement is adapted to convert 90 the continuous rotary movement of a driven member into a movement of the driven member of a variable character in which periods of comparative rest intervene between others in which the driven member partakes of an 95 angular movement of more or less extent, and if the proper proportions and relations are adopted this dwell or suspension of movement occurs twice in each rotation of the driven member. 100

A mechanical movement in which an oscillatory intermediate is employed for transmitting motion is not claimed, broadly, in this application, the same being shown, described, and claimed in an application filed by me on April 19, 1900, Serial No. 13,470. 105

Having described my invention, I claim—

1. The combination of a driving-shaft and a driven shaft, a gear fixed on each of said shafts and one gear located within the other 110 and each mounted for and confined to a rotary movement, of an intermediate driven from the driving member and mounted for combined rotary and translational movement; and a crank motion for oscillating the 115 intermediate bodily to and fro in the plane of the driving member.

2. The combination with a driving-gear within a driven gear, said driven gear, and each mounted for and confined to a rotary 120 movement, of an intermediate meshing with the driving member and with the driven member and mounted for combined rotary and translational movement; and a crank motion for oscillating the intermediate bodily 125 to and fro.

3. The combination with a driving-gear within a driven gear, said driven gear, and each mounted for and confined to a rotary 130 movement, of an intermediate driven from

the driving-gear and meshing with the driven gear and mounted for combined rotary and translational movement; a rocker on which said intermediate is mounted and which has 5 a pivotal axis coinciding with the axis of the driving-gear; and a crank motion for oscillating the rocker and thereby oscillating said intermediate bodily to and fro.

4. The combination with inside driving 10 and outside driven members each mounted for and confined to a rotary movement, of an intermediate for transmitting motion from the driving to the driven member, said intermediate being mounted for combined rotary 15 and translational movement; a rocker supporting said intermediate and oscillatable in an arc about the axis of one of said members; and a crank motion for controlling the movements of the rocker.

20 5. The combination with inside driving and outside driven members each mounted for and confined to a rotary movement, of an intermediate for transmitting motion from the driving to the driven member, said intermediate being mounted for combined rotary 25 and translational movement; a shaft from which the driving member is operated; and a crank motion driven from said shaft and controlling the movements of the rocker.

30 6. The combination with an inside driving and an outside driven member each mounted for and confined to a rotary movement, of a gear mounted upon the driven member; an intermediate for transmitting motion from 35 the driving to the driven member, said intermediate being mounted for combined rotary and translational movement; a rocker supporting said intermediate and pivoted concentrically with one of said members; and a 40 crank motion for controlling the movements of the rocker.

7. The combination with a driving member and a driven member mounted one within the other, of a rotatable intermediate member 45 peripherally engaging both the driving member and the driven member and oscillatable in a path which is concentric with both the driving member and the driven member; and a member which has a circular 50 cross-section and is revoluble about an axis eccentric thereto and is adapted to oscillate the intermediate member.

8. The combination of a driving member; an intermediate member peripherally engaged thereby; a driven member which has 55 an internal face engaged by the periphery of the intermediate member and surrounding the driving member; a rocker-arm on which the intermediate member is rotatably mounted; a member which has a circular cross-section and is revoluble about an axis eccentric 60 thereto; and a connection from said eccentrically-rotatable member to the rocker-arm.

9. The combination with a driving gear-wheel within a driven internal gear-wheel, 65 said internal gear, of an intermediate gear-wheel which is driven from the driving gear-wheel and is in engagement with the driven gear-wheel; a rocker upon which the intermediate is mounted; and a crank motion for 70 oscillating the rocker to and fro.

10. The combination with an inside driving and an outside driven member having relatively fixed axes, of an intermediate rotatably mounted between said members; a rocker 75 supporting said intermediate and movable about the axis of one of said members; and a crank motion which is operated from one of said members and controls the to-and-fro movements of the rocker.

80 11. The combination of a driving member and a driven member located one within the other and each of which is mounted for and confined to a rotary movement; a lever which is pivoted concentrically with one of said 85 members; an intermediate which is mounted at one end of said lever and engages both the driving member and the driven member; and a crank motion operatively connected with the other end of said lever and adapted 90 to rock the latter.

12. The combination of concentrically-disposed rotary movable driving and driven gears, the driven one of which has the form of an internal gear and both of which gears 95 are in the same plane transverse to the axis of rotation; and a translationally oscillatory intermediate meshing with said internal gear for transmitting motion from one to the other.
